CLAIM

I claim the ornamental design for a golf tee, as shown and described in the drawings.

DESCRIPTION

FIG. 1 is a top plan view of a golf tee showing my new design.

FIG. 2 is a side elevation view thereof (Identical from any position).

FIG. 3 is a view of the profile of the tee along the central vertical plane. The saucer shaped depression on the top of the tee (on which golf balls are placed for tee shots) is shown; and,

FIG. 4 is a perspective view from above (identical from any position).
